UNITED STATES PATENT OFFICE.

CHARLES S. BEACH, OF BENNINGTON, VERMONT, ASSIGNOR TO H. C. WHITE CO., OF NORTH BENNINGTON, VERMONT, A CORPORATION OF VERMONT.

APPARATUS FOR MOUNTING STEREOGRAPHS.

No. 805,404.

Specification of Letters Patent.

Patented Nov. 21, 1905.

Application filed March 25, 1903. Serial No. 149,564.

To all whom it may concern:

Be it known that I, CHARLES S. BEACH, of the village of Bennington, in the county of Bennington and State of Vermont, have invented 5 certain new and useful Improvements in Apparatus for Mounting Stereographs, of which the subjoined description, in connection with the accompanying two sheets of drawings, constitute a specification.

10 The invention relates to means for mounting gummed stereoscopic prints (commonly called "stereographs") while wet upon stiff card-mounts, applying to the mounted prints ferrotype-plates while still wet, subjecting 15 the assemblage in this condition to initiatory pressure to fasten the several parts together, and delivering the assemblage, which is called a "pack," to a receptacle called a "press-box," which is automatically and intermittently 20 moved along step by step by special mechanism to receive the packs as they are delivered to it. The operations of the press-box carriage are initiated by the automatic action of the pack upon an escapement-lever 25 as it leaves the press-rolls, as will more clearly appear further on.

The mounting-frame 60 (shown in Fig. 2) constitutes an element in some of the combinations herein claimed and is the subject-matter 30 of Letters Patent No. 759,949, dated May 17, 1904, to which reference may be made for specific description thereof.

The drawings fully disclose the invention, wherein—

35 Figure 1 shows a side elevation of the front of the right hand end of the machine with some parts broken away to expose otherwise concealed parts. No part of the frame is shown where it is unessential to a clear understanding 40 of the apparatus. Fig. 2 is a top plan view of the parts seen in Fig. 1. Fig. 3 is an elevation of the rear of the press-box frame and carriage and its actuating apparatus as seen in Fig. 1. Figs. 4, 5, and 6 are respectively front, edge, and front elevations of the scape-wheel and pallets which control the movements of the press-box carriage. Fig. 7 is a side view, and Fig. 8 a rear view, of the pawl - and - ratchet mechanism which is connected 45 with the scape-wheel and box-carriage by the motion of which the scape-wheel rotates a step as each pack passes from under the press-rollers. Fig. 9 shows a transverse

section through one of the crank-wrists of the scape-wheel shaft. Fig. 10 shows a side elevation of those parts of the machine not shown in Fig. 1.

The apparatus is arranged on a long table 1, on opposite sides of which several operatives can sit. Abreast of each operative a 60 mounting-frame 60, Fig. 2, is provided, in which the pasted prints are adjusted and stuck to the cards, as described in said patent. This frame 60 consists simply of a base or tablet T, to the top of which an open-folding 65 gage-frame F is hinged, which has a central cross-bar which makes a right angle with the inner edge of the front member of the gage-frame. This frame is used by placing a card on the tablet in proper position, folding down 70 the gage and fastening it with the catch c. The previously-pasted pictures are then adjusted in position on the card by placing their inner bottom corners accurately in the angles formed by the cross-bar and the inner edge of 75 the frame F, where they are lightly brushed down or simply stuck by their edges or corners, care being taken that the face of the print be not soiled or disturbed when a ferrotype-plate is applied to the print in the usual 80 way. On either side of the table is an endless belt 9, which is carried by the pulleys 3 3, placed one at each end of the table. This belt is called the "picture-carrier," and it is driven by the belt 4, which connects pulley 3 with a 85 driving-pulley 62 on the driving-shaft 27. The action of the picture-carriers is governed by a tightener 48, which is placed under the control of the foot of the operative by the treadle 49, so that he may stop or start it at 90 pleasure. At the left-hand end of the table the paster sits and after pasting the backs of the prints lays them on the carriers 9 9, by which they are carried along opposite the mounters, sitting opposite the frames 60, by 95 whom they are accurately stuck to the cards by the aid of the guide-frame F, as before described. After applying the ferrotype-plate to the face of the pack the mounter then lays the pack on another endless apron 6, which is 100 carried by pulleys or drums 2 and 45, by which it is conveyed to the press-rolls 12 12. This apron is called a "conveyer" and is provided with cross-cleats 7 7 7, which act to push the pack onto the press-table 11 and into the grip 105 of the press-rolls. The conveyer runs con-

stantly and is driven by pulley 63 on driving-shaft 27, through belt 5, which connects pulley 63 with pulley 2. Belt 5 may also be regulated by a tightener 46, the tension of which 5 is regulated by a spring 47 or by any other appropriate means. The press-rollers 12 12 are adjusted to give only a moderate pressure as the pack passes between them, so as simply to stick the several parts of the pack together. 10 The rollers 13 13 are adjusted to an intense pressure, which is designed to firmly close all parts firmly together. As the pack emerges from between the first pair of rollers it is forced under a tripping-roller 16, which lies across its path, and in doing so lifts it slightly. 15 Being hung in the arms of a rock-shaft 17, this slight rise effects slight rotation of the rock-shaft, which causes a slight swing of the arm 18, which it carries on its outer end, as 20 shown in Fig. 1. A rod 19 connects this tripper-arm 18 with an arm 20, carried on the end of the verge-shaft 51, (better seen in Figs. 4, 5, and 6,) which is provided with two pallets 54 and 55, which project from an arm 21, also 25 carried by the verge. This verge is supported in bearings on two upright standards or posts 32 32, and the pallets engage pins *c*, *d*, *e*, and *f* of a scape-wheel 22, which is carried on the end of a double crank-shaft 23, which 30 runs in bearings 43 43, also attached to said posts. On the opposite end of this crank-shaft is a pulley 24, with which some driver (not shown) connects by a loose belt 57, whereby said shaft may be gently propelled, the 35 purpose of this loose driving connection being to carry the crank-shaft over dead-centers, and also to act as a brake on the crank-shaft to ease down the press-box when loaded. The cranks in this shaft are seen at *a* and *b*, 40 Figs. 7, 8, and 9, and are located midway between the posts 32 32. Each of these cranks or eccentrics carries a pawl 35 or 36, Figs. 7 and 8, pivoted thereon, having the weights 37 and 38, respectively, at their lower ends, 45 which are so designed that gravity will normally act to throw the noses of the pawls toward the ratchets 33 33, which are attached to the back side of a carriage 31, on which the press-box is carried and which slides in 50 the ways 64 of posts 32. Beneath the crank-shaft 23 is a fulcrum-bar 39, which spans the interval between the posts, with which the lugs 41 and 42 at the lower ends of the pawls engage as the cranks carry the pawls around. 55 Fig. 7 illustrates the action of the cranks, pawls, and lugs in connection with the ratchets and the fulcrum-bar. The cranks are set opposite each other, as seen in Fig. 9, so that when one pawl is ascending it will not engage its coöperating ratchet, but will be thrown into engagement therewith the instant its lug runs off the fulcrum-bar, so that its weight comes into action. The design is such that the nose of the pawl will throw into engagement a little in advance of its highest. 60

upward movement, and as the throw of the cranks slightly exceeds the length of a ratchet-tooth after the pawl has thrown in further rotation of the crank causes the nose of the pawl to engage the tooth above it and to lift 70 it just enough to take the weight of the carriage and its load off the nose of the other pawl, and this occurs just when the lug at its other crank is approaching the lower part of its throw and while the other lug is in engagement with the bar, so that further rotation of the shaft will draw the nose of the other pawl down and swing it away from the ratchet, the bar 39 serving to hold it away 75 from the ratchet until it has been carried high enough to draw its lug off the bar, when the weight will act to throw it into position to engage the other ratchet. Thus the weight of the carriage and its load is suspended at 80 all times upon the nose of one or the other of the pawls, and at each half-revolution of the shaft the carriage is given a slight upward hitch, which is barely enough to take the weight off the other pawl at the moment of its withdrawal from engagement with its corresponding ratchet. 85

A strongly-made box 311 is provided to receive the packs C as they are delivered from the roller-press which is carried on the box-carriage 31, resting against the bracket 70, 90 Fig. 1. The delivery of the packs after they have passed the tripper-roller 16 is effected by the press-rollers 13, which seize the packs as they are successively fed to them one after another and push them along until they reach 100 the roller 24 at the end of the table 11. This roller is rotated by a belt from a pulley or belt-groove in one of the roller-arbors and operates to positively carry the pack along until it drops over the roller into the box. 105 All this is clearly shown at C in Fig. 1, where the box is shown in position partially filled. When the box is full, it is removed from the carriage and another substituted. After removal the contents of the boxes are firmly 110 pressed together therein and blocked, so that they can set and partially dry out in that condition. 115

The construction and operation of the escapement mechanism presents some novelties. The verge 21 is limited in its throw by the stationary pins 52 and 53. The dormant position of the scape-wheel and pallets is as seen in Fig. 4, with a pin, as *d*, resting on the pallet 54. A swing of arm 21 over against stop-pin 52 releases pin *d*, and the scape-wheel rotates under the influence of belt 57 or the weight of the box-carriage until the following pin *e* strikes the upper face of pallet 55; but this face being beveled or inclined the force or momentum of the scape-wheel will force it back until the back edge of arm 21 strikes stop-pin 53, at which moment pin *e* will slide off the pallet 55 and drop onto pallet 54, where it will rest until the tripper mechanism is 120 125 130

again started by the passage of another pack under the tripper-roller 16, when this operation will be repeated. It will be noticed that the recoil movement of pallet 55 will reset the 5 tripper-roller 16 for the next pack. The scape-wheel may be perforated for as many pins as may be found expedient, and the pins should be removable. This is desirable to accommodate the action of the press-box to the varying 10 thicknesses of the packs. The object sought is to keep the top of the pile of packs in the press-box at just the proper elevation with reference to the delivery end of table 11 that as the packs fall over the roller 24 they 15 will drop into true position in the box. There should be as many pins on each side of the scape-wheel as it requires packs to fill the box to the depth of one tooth of the ratchet.

It will be seen that the scape-wheel pins are 20 not disposed around the entire periphery of the wheel or disk 22, but coincide with the position of the crank-wrists, which positions are indicated in Figs. 4 and 6 in dotted lines. The reason for this disposition is that the 25 pawls can only move effectively in lowering the box-carriage when the crank-wrist is moving through that part of its orbit closest to and most nearly parallel with the line of ratchet-teeth, or, in other words, while it is 30 traversing an arc of which the extremities are equidistant from a line drawn through the axis of the crank-shaft perpendicular to the line of movement of the ratchet-bar. It is plain that while the crank-wrist is traversing 35 the dead-central parts of its orbit no appreciable movement will be imparted to the pawl. Hence the scape-pins are placed on the scape-wheel opposite the non-effective parts of the orbit of movement of the crank-wrists. Therefore 40 when the last scape-pin of the series has passed the pallet 54 the scape-wheel rotates without opposition around about a quarter of a revolution, more or less, carrying the upper pawl with it, and thus lowering the box until 45 the leading scape-pin of the next series strikes pallet 55. Thus one complete revolution of the scape-wheel will lower the press-box two notches of the ratchet or a distance equivalent to the thickness of about eight packs as they 50 are deposited in the box from the table 11 over the roller 24.

I therefore claim as my invention, and desire to secure by Letters Patent, the following:

55 1. In a stereograph-mounting apparatus, a table equipped with a series of mounting-frames, a print-carrier for transferring the pasted prints from the paster to the mounter, a conveyer for delivering the mounted pack 60 to the roller-press, and a roller-press for closing together the constituent parts of the pack, substantially as specified.

2. In a stereograph-mounting apparatus, the combination of a table equipped with a series

of mounting-frames, a print-carrier for transferring the pasted prints from the paster to the mounter, a conveyer for delivering the mounted prints to a roller-press, a roller-press, and a press-box for receiving the mounted prints, substantially as specified. 65

3. In a stereograph-mounting apparatus, the combination of a table equipped with a series of mounting-frames, a print-carrier for transferring the pasted prints from the paster to the mounter, a conveyer for delivering the 70 mounted prints to a roller-press, a roller-press, a press-box for receiving the mounted prints, a carriage upon which the box is carried, and mechanism interposed between the press and the carriage adapted to be operated 75 by the transit of a pack for advancing the press-box a definite distance, substantially as specified.

4. The combination with the roller-press and the box-carriage of a pawl-and-ratchet mechanism for dropping the carriage by a step-by-step movement, of an escapement consisting of a scape-wheel, verge and pallets, and a tripping device for actuating the pallets provided with a member which normally lies in 85 the path of the pack as it passes through the roller-press, whereby the passage of the pack displaces the tripper and thereby, through the connection with the escapement causes the scape-wheel to rotate one step, substantially 90 as specified.

5. The combination of the scape-wheel and its shaft having oppositely-disposed crank-wrists, pawls journaled on said wrists, ratchets with which said pawls are adapted to engage, a fulcrum-bar with which said pawls collide to evert their noses from engagement with said ratchets on the forward part of their stroke, and means to operate said scape-wheel, substantially as described. 100

6. The combination with the roller-press of the tripping and escapement mechanism, press-box, box-carriage and attached ratchets, the scape-wheel and its crank-shaft and pawls carried in the latter and fulcrum-bar for tripping 110 said pawls and intermittently lowering said box, substantially as specified.

7. The combination with the ratchets, scape-wheel, verge and pallets, cranks and fulcrum-bar, of the pawls having provisions for engaging the bar to disengage their noses from the ratchets, and means for normally throwing their noses into engagement with the ratchets, the throw of the cranks being slightly greater than the pitch of the ratchet-teeth, all adapted to operate substantially in the manner described and for the purposes set forth. 115

8. The combination of the scape-wheel and its shaft having oppositely-disposed crank-wrists, pawls journaled on said wrists, ratchets with which said pawls are adapted to engage, a fulcrum-bar with which said pawls collide to evert their noses from engagement 120

125

with said ratchets on the forward part of their stroke, pins on said scape-wheel opposite said crank-wrists, a verge and pallets to engage with said escapement-pins, and means for actuating said verge and ratchets, substantially as specified.

In testimony whereof I have hereto sub-

scribed my name, at the village of North Bennington, Vermont, this 12th day of March, A. D. 1903, in the presence of two witnesses. ¹⁰
